CLAIM

The ornamental design for the overcap, as shown and described.

DESCRIPTION

FIG. 1 is an isometric view of the front, top and right side of the overcap showing our new design;

FIG. 2 is a front elevational view of FIG. 1;

FIG. 3 is a rear elevational view of FIG. 1;

FIG. 4 is a right side elevational view of FIG. 1;

FIG. 5 is a left side elevational view of FIG. 1;

FIG. 6 is a top plan view of FIG. 1; and,

FIG. 7 is a bottom plan view of FIG. 1.

The broken lines are included for the purpose of illustrating portions of the overcap and environmental structure that form no part of the claimed design.
